(**) Term: **14 Years**

(57) **CLAIM**

(21) Appl. No.: **29/152,350**

The ornamental design for a device for connecting computer
devices, as shown and described.

(22) Filed: **Dec. 14, 2001**

DESCRIPTION

(51) LOC (7) Cl. **14-02**

FIG. 1 is a front elevational view of the device for connecting
computer devices of the present invention;

(52) U.S. Cl. **D14/433**

FIG. 2 is a rear elevational view of the device for connecting
computer devices of FIG. 1;

(58) Field of Search D14/432-438;

FIG. 3 is a left side elevational view of the device for
connecting computer devices of FIG. 1;

D13/182; 463/30-35, 43-47; 273/148 B;

FIG. 4 is a right side elevational view of the device for
connecting computer devices of FIG. 1;

439/607, 638, 676, 946, 540.1; 361/684,

FIG. 5 is a top plan view of the device for connecting
computer devices of FIG. 1; and,

686-689, 737

FIG. 6 is a bottom plan view of the device for connecting
computer devices of FIG. 1.

(56) **References Cited**

The broken lines showing of wording in FIGS. 1 and 2 are
for illustrative purposes only and form no part of the claimed
design.
